Patented Aug. 13, 1918.

FIG-1-

FIG-2

UNITED STATES PATENT OFFICE.

JOHN C. BLACK, OF LOS ANGELES, CALIFORNIA, ASSIGNOR TO STANDARD OIL COMPANY,
OF RICHMOND, CALIFORNIA, A CORPORATION OF CALIFORNIA.

PROCESS OF PRODUCING GASOLENE.

1,275,648.

Specification of Letters Patent. Patented Aug. 13, 1918.

Application filed February 21, 1916. Serial No. 79,525.

To all whom it may concern:

Be it known that I, JOHN C. BLACK, a citizen of the United States, residing at Los Angeles, in the county of Los Angeles and State of California, have invented certain new and useful Improvements in Processes of Producing Gasolene, of which the following is a specification.

My invention relates to the production of gasolene. Its object is to increase the yield of gasolene from crude oil.

The nature of my process and the manner in which it is carried out will now be fully described.

15. In the ordinary distillation of crude petroleum, a continuous distillate is formed, varying continuously in gravity and boiling points. In the commercial production of marketable oils, certain cuts are made in the 20 distillate stream, determined by its gravity, these cuts being designated by various names, and used for various purposes, having been found by experience to be suitable for such purposes. For instance, a distillate 25 cut from the stream whose average gravity is 60° Baumé, will be called gasolene, and its boiling points will vary from, say 95° Fahr. to 350° Fahr.

Another cut may be made, the gravity of 30 which will be 48° to 50° Baumé. This will be called engine distillate, and its boiling points will range from 150° Fahr. to 450° Fahr.

Any number of cuts may be made, of any 35 gravity desired, and the boiling points of any such cut will range from that of the lightest fraction in the mixture to that of the heaviest. The boiling points most usually taken are the first, or initial, and 40 the last, or final boiling point. This indicates to the refiner just what cuts have been taken to make that particular grade of oil.

In the usual production of gasolene, a cut 45 is made whose gravity is about 60° Baumé, and whose boiling points are approximately those previously given for gasolene. There is also produced a large yield of oil of a much lower Baumé gravity than gasolene, viz., around 50° Baumé, which is not suitable for the general uses of gasolene. This 50 low Baumé gravity stock is usually called engine distillate, and in the following specifications, when I mention engine distillate, I will mean the above mentioned low Baumé

gravity oil, and when I speak of gasolene, 55 I will refer to the high Baumé gravity oil as above described.

By my process, I convert engine distillate, an oil of a low Baumé gravity, into gasolene, an oil of a high Baumé gravity. This 60 process I carry out in the following manner:

In making fractional distillations of gasolene and engine distillate, I have observed the fact that both oils contain certain fractions, the boiling points of which are identical, that is, their boiling points overlap in the higher ranges of the one and the lower ranges of the other, the high boiling fractions of gasolene being identical with the 65 low boiling fractions of engine distillate. I have discovered that under the proper conditions of temperature and pressure, it is possible to convert engine distillate into gasolene, by passing a hydrocarbon gas, particularly gas from an oil well, or gas well, that is, natural gas, through the oil held in a suitable container, the gas being forced through the engine distillate, preferably under high pressure and low temperature. 70 After a suitable time, which can be determined by the increase in Baumé gravity, or other suitable means, the oil is withdrawn and distilled, preferably with the use of steam. The distillate thus obtained can be 75 separated into fractions, one of which will have a gravity of 60° Baumé, and boiling points identical with those of natural gasolene obtained from crude oil distillation. A cut can also be made, the gravity of which 80 will be identical with the original stock subjected to the gas treatment. A further cut can be made, the gravity of which will be within the range of that of burning oil, or kerosene. 85

The yield of gasolene will vary considerably with the character of the gas, with temperature, and with the pressure. I have obtained results where fifty per cent. of the engine distillate is converted into gasolene; 100 but I have found that the most economic result is obtained when a conversion is made of twenty-five to thirty per cent., i. e., the maximum yield per thousand cubic feet of gas used is obtained when, upon fractionation, a conversion of twenty-five to thirty per cent. is made.

The engine distillate obtained upon frac-

tionation, after treating with gas, can be mixed off in a new charge, and a further conversion into gasoline made, the heavy bottom cut in each case being separated and used for other purposes, not vital to the process.

By this process a gasoline is produced that is identical with natural gasoline in gravity, initial and final boiling points, and 10 in vapor tension. The gasoline produced by my process is not similar to that produced by taking casing-head gasoline, which is produced by compressing gas and extracting therefrom a high Baumé gravity oil, and 15 mixing this off with a heavy distillate. In this last named case the gravity may be standard, but the boiling points will be low in the initial and high in the final, and the vapor tension will be high in comparison 20 with natural gasoline, or with the gasoline I produce. A high vapor tension makes the oil dangerous to transport, due to its tendency to create a high pressure when its temperature becomes elevated, and a high 25 final boiling point tends to produce a carbon deposit in the cylinders of gasoline engines, when such a gasoline is used for that purpose.

The following is an example of my 30 process:

Treating 100 gallons of a low grade distillate (commonly called engine distillate, and having a gravity of 48° Baumé and an initial and a final boiling point of 170° 35 Fahr. and 436° Fahr., respectively) with 15,000 cubic feet of natural gas, after same has passed through a compressor plant to take out the casing-head gasoline, and under a temperature of 70° Fahr. and a gage pressure of 160 pounds, will cause the absorption 40 of the gas by the distillate in a period of one hour and forty minutes. From the mixture thus formed, I derive, upon subsequent steam distillation, a fraction or cut of gasoline amounting to 29.3% of the original 45 volume of distillate, said gasoline having a gravity of 59.5 Baumé and an initial and final boiling point of 94° and 331° Fahr., respectively. This is well within the range 50 of the boiling points of natural gasoline, obtained from crude oil distillation.

I also obtain a cut of engine distillate, the gravity of which is 48° Baumé, and the initial boiling point 216° Fahr., and the 55 final boiling point 390° Fahr. The yield of such engine distillate is 60.7% of the original volume of distillate. This engine distillate is well within the range of that obtained from crude oil distillation.

60 The 10% residue left in the still has a gravity of 42° Baumé, which is within the range of burning oil or kerosene.

The foregoing example is merely a statement of details in a given case. I am not 65 to be bound by these specific details, how-

ever, for these may vary under conditions which are well within the knowledge and practice of refiners.

In using the term "conversion" herein as applied to the change in the engine distillate, which occurs by the absorption of the hydrocarbon gas and which results in the subsequent recovery by ordinary steam distillation of a gasoline cut of the character and volume stated, I am to be understood 70 as meaning any change, probably, physical, by which the engine distillate is made to yield, under the process described, a gasoline cut not heretofore found in or recoverable from such distillate and far in excess of the 80 gasoline contained in the hydrocarbon gas absorbed.

The steam still used in the subsequent distillation of the gas treated engine distillate is that in general use by oil refiners, in 85 which the heat of vaporization is furnished by open steam, that is, steam admitted into the body of the oil, thereby heating it and vaporizing the volatile constituents of the oil. The steam may be obtained from any 90 source, direct from a boiler, or exhaust steam from pumps or engines may be used. The pressure only needs to be sufficient to overcome the pressure in the still and the depth of the oil body, over the steam injection 95 pipes. This pressure may not exceed three to four pounds, the steam having a temperature of 220° Fahrenheit or thereabout.

I am aware that it is an old and well known process to absorb vapors, or particles 10 of oil that are entrained in a gas, by passing the latter through a heavy oil, and, on distillation, to recover the absorbed vapor, leaving the heavy oil to be used again as an absorber, with no change in its characteristics. This, however, is essentially different 11 from my process, as I bring about a change in the absorbent oil itself, and on distillation obtain a new oil, yielded from itself, having different characteristics from the original oil, this new oil being a more valuable product than the original oil.

Any suitable apparatus may be used in which the treatment of the engine distillate with the natural gas may be carried out.

In the accompanying drawings, I show two simple forms of apparatus.

In these drawings—

Figure 1 is a view of one form of apparatus.

Fig. 2 is a view of another and preferred form of apparatus in which the oil and gas proceed in counter current, a condition tending 1 to the highest efficiency.

In Fig. 1, the tank 1 is fitted with a valve 1 controlled pipe 2 for supplying the low gravity oil to be treated, a storage tank for said oil being shown at 3, and a pump 4 being indicated as a means for supplying 1 said oil.

The tank 1 is also fitted with a valve controlled pipe 5 for withdrawing the charge after it has been treated with the gas. This pipe 5 is shown as leading into a storage tank 6 for the gas-treated oil, and from this last named tank a valve-controlled pipe line 7 leads to the steam still, not shown. 8 is the valve controlled gas inlet pipe, to the tank 1, the end of said pipe within the tank having a perforated distributor 9. 10 is a valve controlled outlet pipe for withdrawing the gas after treating the oil.

In Fig. 2, the gas-absorber comprises a treating tank 11 which has a valve controlled supply pipe 12 for a continuous stream of oil introduced, preferably, at or near the top of the tank, said pipe receiving its supply from the storage tank 13 and a pump 14. The treating tank also has 20 within it a series of trays 15 with overflows 16, and over these trays the oil continuously and successively passes, meeting the upgoing gas which is introduced at the bottom of the tank by a valve controlled pipe 25 17, the gas being discharged into each tray-full of oil, by distributors 18, thereby making the two streams, one of oil and the other of gas, pass counter-current to each other. 19 is a valve controlled gas-outlet pipe from 30 the top of the treating tank. 20 is a valve-controlled outlet pipe for the treated oil, leading from the lower portion of the treating tank to a gas-treated oil storage tank 21, from which a valve-controlled line pipe 35 22 leads to the steam still, not shown.

Although I have herein expressed a preference for the use of natural gas from an oil or gas well, I may use a hydrocarbon gas otherwise derived or from a different 40 source, as, for example, still-gas from the distillation of petroleum, or coal tar or from the distillation of any hydrocarbon. The use of natural gas has, however, special 45 advantages, such as its great abundance, its availability and its richness in those qualities necessary for its action in the present connection.

I claim:

1. The process of producing gasolene 50 which consists in a conversion of a cut in the fractional distillation of petroleum whose boiling points lie within the final boiling point of the gasolene cut and whose Baumé gravity lies below that of said gasolene cut, by absorbing in said low gravity cut a hydrocarbon gas at approximately normal temperature, and subsequently distilling said gas-treated cut and recovering therefrom a cut identical in its gravity, its 55 boiling-point range, and its vapor tension

with gasolene obtained from the natural distillation of petroleum.

2. The process of producing gasolene which consists in a conversion of a cut in the fractional distillation of petroleum whose boiling points lie within the final boiling point of the gasolene cut and whose Baumé gravity lies below that of said gasolene cut, by absorbing in said low gravity cut natural gas at approximately normal 70 temperature, and subsequently distilling said gas-treated cut and recovering therefrom a cut identical in its gravity, its boiling-point range, and its vapor tension with gasolene obtained from the natural distillation of petroleum. 75

3. The process of producing gasolene which consists in taking that cut in the fractional distillation of petroleum, whose initial boiling-point range overlaps the final 80 boiling-point of the gasolene cut of said distillation, and whose Baumé gravity lies below that of said gasolene cut, and converting those fractions of the cut so taken which are identical in boiling point with certain 85 fractions of said gasolene cut, by causing the absorption of a hydrocarbon gas at approximately normal temperature by the cut so taken, and then fractionally distilling said gas-treated cut and recovering therefrom the converted fractions in a cut identical in its gravity, boiling-point range and vapor tension with gasolene obtained from the natural distillation of petroleum. 90

4. The process of producing gasolene 95 which consists in taking that cut in the fractional distillation of petroleum, whose initial boiling-point range overlaps the final boiling-point of the gasolene cut of said distillation, and whose Baumé gravity lies 100 below that of said gasolene cut, and converting those fractions of the cut so taken which are identical in boiling point with certain fractions of said gasolene cut, by causing the absorption of natural gas at approximately normal temperature by the cut so taken, and then fractionally distilling said gas-treated cut and recovering therefrom the converted fractions in a cut identical in its gravity, boiling-point range and 110 vapor tension with gasolene obtained from the natural distillation of petroleum. 105

In testimony whereof I have signed my name to this specification in the presence of two subscribing witnesses.
